UNITED STATES PATENT OFFICE.

ROBERT L. STEVENS, OF ALBION, MICHIGAN, ASSIGNOR TO NATIONAL SPRING & WIRE COMPANY, OF ALBION, MICHIGAN, A CORPORATION OF MICHIGAN.

CUSHION-SPRING.

1,275,318.

Specification of Letters Patent. Patented Aug. 13, 1918.

Application filed December 2, 1916. Serial No. 134,560.

To all whom it may concern:

Be it known that I, ROBERT L. STEVENS, a citizen of the United States of America, residing at Albion, in the county of Calhoun 5 and State of Michigan, have invented certain new and useful Improvements in Cush-
ion-Springs, of which the following is a specification, reference being had therein to the accompanying drawings.

10 The invention relates to cushion or seat springs of that type known as double-deck, in which there are two or more springs of different tension placed in end-to-end relation to each other. It is the object of the
15 invention to obtain a construction in which the springs of the double-deck are easily and securely fastened to each other and are also anchored to an intermediate frame to prevent lateral displacement. To this end the
20 invention comprises the construction as hereinafter set forth.

In the drawings:

Figure 1 is a perspective view of one of the strips forming the securing and anchor-
25 ing connection between the double-deck
springs;

Fig. 2 is a plan view showing the manner of engaging the springs of the upper deck with said strip;

30 Fig. 3 is a longitudinal section through the strip engaged with the upper deck springs and in the act of engagement with the lower deck springs;

Fig. 4 is a similar view with the upper
35 and lower decks secured to each other;

Fig. 5 is a section through the completed structure.

A are the springs of the lower deck, which are preferably formed of wire of a
40 larger gage than those forming the upper deck so as to be of greater tensile strength. These lower deck springs are first assem-
bled and secured to a suitable supporting base frame, which as shown comprises a
45 wire border frame B and a series of cross-
strips C, said strips being secured to the springs by struck-out tongues D clenched over the base coils thereof. To secure the upper deck springs in position, these are
50 first attached to sheet-metal strips E, which have struck-out therefrom the tongues F initially arranged in a plane parallel to the plane of the strip and positioned to em-
brace the base coil G of each upper deck
55 spring from diametrically opposite sides

thereof. The springs are placed in engage-
ment by slipping them laterally beneath the
tongues F, as illustrated in Fig. 2. The
tongues are then bent downward to extend
through the apertures H in the strip formed 60
by the original striking-out of the tongues,
as shown in Fig. 3. The strips E are then
assembled in an intermediate frame, prefer-
ably comprising a border wire I which has
kinks or bends J therein for positioning and 65
locking the ends of the strips. The latter
are provided with tongue portions K at
their ends, which are bent over the links
J and when clenched thereto will serve to
securely hold the strips within the frame I. 70
The frame I with the upper deck springs
secured thereto is then placed over the
frame B with the lower deck springs, and
the depending tongues F are inserted within
the upper coils of the registering lower 75
deck springs. A suitable clenching tool is
then used to turn over these tongues, as
shown at L, Fig. 4, which will lock the two
decks to each other and also securely hold
the complementary upper and lower springs 80
in registration with each other.

The construction as described is one in which the elements may be formed at small cost, while the operation of assembly is quickly performed. When complete the 85
springs for both decks are securely posi-
tioned and anchored so as to avoid danger
of accidental displacement.

What I claim as my invention is:

1. In a cushion spring, the combination 90
with lower and upper abutting deck springs,
of a sheet-metal strip having struck-out
tongue portions for embracing the coils of
one of the decks, said tongues being also
bent into engagement with the abutting coil 95
of the other deck to secure said decks to each
other.

2. In a cushion spring, the combination
with lower and upper abutting deck coil 100
springs, of a sheet-metal strip extending be-
tween the abutting coils of the lower and
upper decks, said strip having struck-out
tongues for embracing the base coil of one
deck and bent through the aperture in the 105
strip into engagement with the coil of the
other deck to secure said decks to each other.

3. A cushion spring, comprising lower
and upper abutting deck coil springs, an
intermediate frame comprising a border 110
wire and cross-strips of sheet-metal ar-

ranged in alinement with rows of springs, said strips being provided with struck-out tongues for embracing the base coils of the upper deck springs and bent downward through the apertures in said strip and clenched about the abutting coils of the lower deck springs.

4. In a cushion spring, the combination with lower and upper abutting deck springs,

of an intermediate frame, and means extending from one side of said frame and embracing the adjacent coil of the deck spring upon said side, said means extending upon the opposite side of said frame and embracing the adjacent coil of the deck spring upon said opposite side.

In testimony whereof I affix my signature.
ROBERT L. STEVENS.
